RECTIFICATION OF GASEOUS MIXTURES

Manson Benedict, Westfield, N. J., assignor to
 Hydrocarbon Research, Inc., New York, N. Y., a
 corporation of New Jersey

Application June 18, 1949, Serial No. 99,956

5 Claims. (Cl. 62—175.5)

1

This invention relates to the production of oxygen by the liquefaction and rectification of air under relatively low pressures, i. e., pressures not substantially above that required to overcome friction losses in the flow of the gas streams through the equipment in which the process is carried out.

All temperatures herein are in degrees F., pressures in pounds per square inch gauge and percentages by volume, unless otherwise specified.

Among the objects of this invention is to provide a low pressure process of producing oxygen by the liquefaction and rectification of air which involves a material reduction in the power consumption required for its practice.

Another object is to provide such process which can be carried out in rectification equipment of smaller volumetric capacity with consequent saving in the cost of the rectification equipment.

Other objects and advantages of this invention will be apparent from the following detailed description thereof.

In accordance with this invention, the air is compressed to a pressure not substantially in excess of that required to overcome friction losses involved in the flow of the air and the rectification products through the equipment. The compressed air after cooling by heat exchange with one or more rectification products is introduced into a rectification system in which liquid reflux at the bottom of the rectification system and at an intermediate level of the rectification system is subjected to re-boiling and the resultant vapors passed upwardly through the system. The top gaseous rectification product, i. e., nitrogen, passes from the top of the rectification system through a heat exchange zone wherein it is warmed by indirect heat exchange with the incoming air stream and/or a recycle stream of the top gaseous rectification product which is subsequently used to effect the aforesaid re-boiling of liquid reflux in the rectification system. Part of the warmed top product is withdrawn as top product and another part forms the recycle stream. The recycle stream is compressed, cooled to remove the heat of compression, and divided into two portions. One portion of the compressed recycle stream is cooled by indirect heat exchange with a rectification product stream and then utilized to re-boil the liquid reflux at an intermediate level of the rectification system. The other portion of the recycle stream is further compressed, cooled to remove the heat of further compression, passed in indirect heat exchange with a rectification product stream to effect further cooling thereof and then utilized to re-boil the liquid reflux at the bottom of the rectification system. The two portions of the recycle stream are at least partially liquefied while effecting the re-boiling of the liquid reflux of the rectification system and both partially liquefied portions are passed through

2

expansion valves whereby the pressure of each portion is reduced to substantially the same pressure existing at the top of the rectification system and thus each portion is further cooled. Both expanded and cooled portions of the recycle stream are discharged into the top of the rectification system to supply liquid reflux thereto. The recycle stream thus is reunited with the top gaseous rectification product stream which, as already described, passes from the top of the rectification system through a heat exchange zone and then is partly removed as top product and partly returned to the rectification system as the recycle stream.

15 In the accompanying drawing, forming a part of this specification and showing for purposes of exemplification preferred arrangements of rectification system and heat exchangers for practicing the process of this invention,

20 Figure 1 illustrates one arrangement of such equipment; and

Figure 2 illustrates a modified arrangement.

It will be understood the drawing illustrates diagrammatically preferred apparatus for practicing the process of this invention and that the invention may be carried out in other apparatus. For example, any desired number of exchangers of either the recuperator or regenerator type may be used in lieu of the exchangers shown in the drawing; and each of the exchangers shown in the drawing may be replaced by two or more similar exchangers placed in series and/or parallel if desired.

In the drawing, in which like reference characters indicate like parts, referring first to Figure 1, A is an air cooling exchanger, B a second exchanger and C the rectification system consisting of an upper section 10 and a lower section 11. In exchanger A air and nitrogen flow in indirect heat exchange relation. Exchanger A has two flow paths 12 and 13 provided with fins of high heat conducting material such as copper or aluminum for promoting rapid and efficient heat exchange between the gaseous media flowing therethrough. For purposes of illustration and in the interest of simplicity the exchanger is shown as comprising two parallel flow paths. Actually, however, each path in each exchanger may comprise a multiplicity of tubes for flow therethrough. As the construction of the heat exchanger per se does not form a part of this invention and as it may be of any well known type, it is believed further description thereof is unnecessary.

45 Exchanger B has four flow paths 14, 15, 16 and 17 each of which may be of the same construction as the flow paths 12 and 13 of exchanger A hereinabove described.

Air line 18 leads into the flow path 12 of the air cooling exchanger A. Line 19 leads from the exit end of path 12 to an intermediate point 21

in the upper section 10 of the rectification system C. Desirably, the rectification system C comprises two sections 10 and 11 each provided, as customary, with rectification plates of the bubble cap or other desired type. Both sections 10 and 11 are operated at a pressure which differs from the inlet pressure by the pressure drop which takes place in the flow of the air through the system. In general the pressure will not exceed about 6 pounds per square inch.

A line 22 leads from the top of column section 10 and is provided with branches 23, 24, branch 23 leads to flow path 13 for supplying this path with a stream of nitrogen product flowing therethrough in indirect heat exchange relation with the air flowing through path 12. The nitrogen warmed in its flow through path 13 leaves this path through an exit line 25. Branch 24 communicates with path 14 of exchanger B. A liquid nitrogen reflux line 26 leads into the top of section 10.

The base of section 10 is provided with a line 27 through which reflux liquid is withdrawn. Line 27 passes through a heat exchanger 28 and communicates with branches 29 and 30. Branch 29 leads into the base of section 10. Line 27, heat exchanger 28 and branch 29 constitute re-boiler R¹ communicating with the base of section 10. Branch 30 is provided with a valve 31 for controlling flow therethrough and leads into the top of section 11, desirably of somewhat smaller volumetric capacity than section 10.

Section 11 is provided with a line 32 for the flow of vapor from the top of this section into the base of the upper section 10. The base of section 11 is provided with a line 33 for the flow of reflux liquid through an exchanger 34. Line 33 communicates with a return line 35 which leads into the base of section 11. Line 33, exchanger 34 and return line 35 constitute re-boiler R² communicating with the base of section 11. Oxygen line 36 leads from the base of section 11 into path 16 of exchanger B. An exit line 37 leads from the exit end of this path.

From path 14 a line 38 leads into the nitrogen exit line 25. Communicating with line 25 is a line 39 which leads into a compressor 40 of any well known type. From the compressor the compressed gas flows through a cooler 41 and thence into a line 42 provided with two branches 43 and 44. Branch 44 communicates with a second compressor 45 and branch 43 with the flow path 15 of the exchanger B. The exit end of this flow path is provided with a line 46 which leads into the heat exchanger 28. A line 47 provided with an expansion valve 48 therein connects exchanger 28 with the liquid nitrogen reflux line 49 at 50.

From the compressor 45 the gas further compressed therein, flows through a cooler 51 thence through line 52 into the flow path 17 of exchanger B. This flow path is provided with an exit line 53 provided with branches 54 and 55, the latter branch leads into the heat exchanger 34. A line 56 provided with an expansion valve 57 connects exchanger 34 with the reflux line 49 at 58. Line 49 communicates with the reflux line 26 leading into the top of section 10.

Branch 54 leads into a refrigerating system 59 of any well known type for supplying a refrigerating medium, such as boiling methane, for cooling the nitrogen passing through the refrigerating system. The system operates to cause the flow of the refrigerating medium in indirect heat exchange relation with the nitrogen, the rates of flow and temperatures of these media being

controlled so that enough cold is introduced by refrigeration, at this point in the process, to compensate for most if not all of the cold losses resulting from the difference in enthalpy between the incoming air and the outgoing products of rectification and for heat leaks into the system. A line 60 provided with an expansion and flow controlling valve 61 connects the refrigerating system 59 with the reflux line 26.

10 In operation, air compressed to a pressure of from 2 to 10 pounds per square inch is passed through flow path 12 in indirect heat exchange relation with a stream of nitrogen flowing from the top of section 10 through line 22, branch 23 and flow path 13. The thus cooled air flows through line 19 and enters section 13 where it is rectified, producing crude oxygen and the nitrogen product of rectification. In the rectification system nitrogen vapors containing some oxygen rise through the column countercurrent to the descending liquid nitrogen reflux introduced through line 26, the nitrogen reflux liquid being thus vaporized and the reflux liquid becoming progressively richer in oxygen flowing downwardly through the column. The reflux liquid from the base of section 10 passes through line 27 of re-boiler R¹ and is thus partially vaporized. The vapor liquid mixture thus produced flows in part through line 29 into section 10. The remaining liquid flows through line 33 into section 11 where it provides the reflux liquid for this section. The division of liquid between the two streams flowing through lines 29 and 33 is controlled by valve 31.

35 A stream of nitrogen is continuously withdrawn through branch 24, flows through flow path 14 in indirect heat exchange relation with the compressed nitrogen stream flowing through flow path 15. The nitrogen flowing through 14 is thus warmed, exits through line 33 and mixes with the nitrogen flowing through line 25. Of the resultant mixed nitrogen a portion is withdrawn as product through line 62 and the remainder passed through line 39 to compressor 40.

40 45 The nitrogen is compressed in this compressor to a pressure of from 35 to 55 pounds per square inch, the heat of compression removed in cooler 41 and then divided into two streams in its flow from line 42 into the two branches 43 and 44. One stream consisting of approximately from one-fourth to one-third of the nitrogen thus compressed passes through line 43, path 15, into and through line 46 and exchanger 28 where it effects re-boiling of the reflux liquid flowing through this exchanger. The mixture of vapors and liquid thus produced flows in part through line 29 into section 10 providing the vapor rising through this section and in part into the top of section 11 providing the reflux for this section. 50 55 60 65 The nitrogen flowing through exchanger 28 is condensed and the resultant condensate passed through expansion valve 48 whereby the pressure thereon is reduced to a pressure substantially the same as, or slightly above that in the top of section 10.

The remainder of the nitrogen consisting of approximately from three-fourths to two-thirds of the nitrogen compressed in compressor 40 flows through branch 44 and enters a second compressor 45 where it is further compressed to a still higher pressure of the order of 60 to 100 pounds. From this compressor, the nitrogen flows through cooler 51 and line 52 into and through path 17 in indirect heat exchange relation with the oxygen flowing through path 16.

The nitrogen is thus cooled and the cool nitrogen passed through line 53.

A portion of the nitrogen from line 53 is passed through line 54, refrigerating system 59, line 60, valve 61 and into and through line 26. The amount of nitrogen thus passed through line 54 is controlled by the setting of valve 61. Upon flow through valve 61, the pressure of the nitrogen is reduced to a pressure substantially the same as or slightly above that in the top of section 10. In its flow through the refrigerating system 59 refrigeration is imparted to the nitrogen stream sufficient to compensate for most if not all of the enthalpy losses and heat leaks into the system. Further refrigeration is imparted to the nitrogen stream upon its expansion in its flow through valve 61.

The remainder of the nitrogen from line 53 flows through line 55 into and through exchanger 34, where it effects re-boiling of the reflux oxygen liquid flowing from section 11. The oxygen vapors thus produced flow through line 35 to provide the vapor loading for column section 11. Oxygen is passed through line 36, flow path 16 in exchanger B and is withdrawn as product through line 37.

The nitrogen flowing through exchanger 34 is condensed and upon flow of the condensate through expansion valve 57 the pressure thereon is reduced. Both streams of nitrogen condensate thus produced flow into and through line 49 into the line 26 where they mix with the nitrogen flowing through line 26 from line 60. The resultant nitrogen mixture enters the top of section 10 where it serves as reflux liquid.

Uncondensed vapors leave the top of section 11 through line 32 and enter the base of section 10 where they flow countercurrent to descending reflux liquid passing through this section.

The modification of Figure 2 differs from that of Figure 1 chiefly in the following respects:

(1) The rectification system consists of a unitary column instead of the two distinct sections of Figure 1;

(2) The re-boilers are built into the column and are not separate units as in Figure 1;

(3) The exchanger system involves five flow paths and not six as in Figure 1; and

(4) Most if not all of the refrigeration required to compensate for enthalpy losses and heat leaks into the system is provided by expanding a portion of the compressed nitrogen and not by imparting refrigeration thereto from an extraneous source as in Figure 1.

In Figure 2, the exchanger has five flow paths 65, 66, 67, 68 and 69 each provided with fins of high heat conducting material as in the case of the flow paths of exchangers A and B of Figure 1. Air line 70 leads into the flow path 65. Line 71 leads from the exit end of path 65 to an intermediate point 72 in the upper portion of the rectification system C'. Desirably, the rectification system C' comprises a unitary column consisting of an upper portion 73 and a lower portion 74, each provided with rectification plates of the bubble cap or other desired type. Upper portion 73 is closed at its base by a plate 75 forming at the base of portion 73 a receptacle for crude liquid oxygen which is subjected to re-boiling. A passageway 76 extends through this plate 75 and connects the top of the lower portion with the base of the upper portion 73. As in the modification of Figure 1, the rectification column C' is operated at a pressure which differs from the air inlet pressure by the pressure

drop which takes place in the flow of the air through the system.

A line 77 leads from the top of the column C' and is provided with two branches 78 and 79. Branch 78 leads into flow path 66. Branch 79 passes into a heat exchanger 80 which is provided with a line 81 leading therefrom into the flow path 66, entering this flow path at a point somewhat above the point where line 78 enters thereinto. In this way the nitrogen warmed in its flow through exchanger 80 enters flow path 66 at a point therein where the temperature is substantially the same as that of the nitrogen flowing through line 81. Nitrogen thus introduced into path 66 flows therethrough, is warmed and leaves this path through an exit line 82.

Communicating with line 82 is a line 83 which leads into a compressor 84 of any well known type. From this compressor compressed gas flows through cooler 85 and thence into a line provided with two branches 86 and 87. Branch 86 communicates with a compressor 88 and branch 87 with the flow path 67. The exit end of this flow path is provided with a line 89 which communicates with a coil 90 immersed in the body of crude liquid oxygen maintained at the base of the upper portion 73 of the rectification column C'. A line 91 provided with an expansion valve 92 leads from this coil 90 into a liquid nitrogen reflux line 93. The coil 90 immersed in the body of crude liquid oxygen corresponds to the re-boiler R¹ of Figure 1.

From compressor 88, the nitrogen further compressed therein, flows through a cooler 94 and thence through line 95 into the flow path 69. From the exit end of this flow path a line 96 leads into a coil 97 immersed in the body of liquid oxygen maintained at the base of the lower portion 74 of the rectification system C'. A line 98 extends from coil 97 through exchanger 80 and is provided with an expansion valve 99. This line communicates with the liquid nitrogen reflux line 93 leading into the top of the rectification column C'. The coil 97 immersed in the body of liquid oxygen corresponds to re-boiler R².

A second line 100 leads from near the base of flow path 69 into an expander 101 which may be an expansion engine or turbine of any conventional type. Line 102 leads from this expander and communicates with the line 78 entering flow path 66. The nitrogen passing through expander 101 is expanded producing most if not all of the refrigeration necessary to compensate for enthalpy losses and heat leaks into the system. Some refrigeration is also produced upon expansion of the nitrogen streams flowing through the expansion valves 92 and 99.

An oxygen line 103 leads from near the base of column portion 74 to the flow path 68. An oxygen product exit line 104 leads from the top of this flow path.

One example of the operation of the process of this invention in the apparatus shown in Figure 2 of the drawing is described below. It will be understood this example is given for purposes of exemplification only and the invention is not limited thereto. The example refers to an oxygen plant operating in a locality where the atmospheric pressure is 14.7 pounds per square inch absolute.

Air which has been treated to remove therefrom condensable impurities, such as moisture and carbon dioxide, is compressed to a pressure of about 6 pounds and at a temperature of 77° F.

introduced into flow path 65. The air is introduced at the rate of 144 tons per hour. It flows therethrough in indirect heat exchange relation with the nitrogen flowing through path 66. The air is thus cooled to a temperature of -309.4° F. and at this temperature and a pressure of 4 pounds enters the rectification column C' at 72. Nitrogen rectification product at a temperature of -318° F. and a pressure of 3 pounds is withdrawn from the top of column C' through line 77. 25.5% of this nitrogen flows through line 79, exchanger 80 where its temperature is raised to -294.9° F., then through line 81 entering the flow path 66 at a point where the temperature therein is approximately -294.9° F.

The remainder of the nitrogen (74.5%) from the top of the rectification column mixes with the nitrogen from the expander 101 which is also at a temperature of -318° F. and a pressure of 3 pounds and flows through line 78 into flow path 66. Nitrogen is withdrawn through line 82 at approximately atmospheric pressure and a temperature of 72° F. About 108.5 tons per hour of nitrogen consisting of approximately 99% by volume of nitrogen is withdrawn as product through line 105.

The remainder of the nitrogen is passed through line 83 into the compressor 84 where the nitrogen is compressed to a pressure of about 37 pounds. The nitrogen flows through cooler 85 where the heat of compression is removed and at a temperature of 77° F. and a pressure of 37 pounds flows in part through line 87 into the flow path 67 and the remainder flows through line 86 to the compressor 88. Approximately 124.5 tons per hour of nitrogen is recycled. Of the recycled nitrogen approximately 25% is passed through line 87 into the flow path 67 and the remaining 75% introduced into the second compressor 88.

The nitrogen leaves flow path 67 at a temperature of -298.2° F. and a pressure of 35 pounds, flows through coil 90 where it is condensed and effects vaporization of the crude liquid oxygen providing part of the vapor rising through portion 73 of column C'. From the coil 90 the condensed nitrogen at a pressure of 34 pounds flows through line 91, is flashed in its flow through valve 92 to a temperature of -318.2° F. and a pressure of 3 pounds at which temperature and pressure it enters the reflux line 93 leading into the top of the rectification system.

In the compressor 88 the nitrogen is compressed to a pressure of about 62 pounds. This compressed nitrogen flows through cooler 94, where the heat of compression is removed, and thence through line 95 into flow path 69 entering this flow path at a temperature of 77° F. and a pressure of 62 pounds. Of the nitrogen flowing through flow path 69, about 65% flows through line 96. This portion of the nitrogen at a temperature of -289.9° F. and a pressure of 60 pounds flows through coil 97 at the base of the portion 74 of the rectification column effecting vaporization of the liquid oxygen in which the coil is immersed, the vapors rising through the lower portion 74 of the column countercurrent to the descending reflux liquid provided by the overflow of the crude liquid oxygen maintained at the base of upper portion 73 which overflow passes through the passageway 76 into the top of portion 74.

The nitrogen in its flow through coil 97 is condensed. The liquid nitrogen thus produced at a temperature of -289.9° F. and a pressure of 59 pounds flows through line 98 and exchanger 80

5 in indirect heat exchange relation with the gaseous nitrogen flowing through line 79 into this exchanger. From exchanger 80 the nitrogen at a temperature of -303° F. and a pressure of 58 pounds flows through the expansion valve 99 where it is flashed to a temperature of -318.2° F. and a pressure of 3 pounds. At this temperature and pressure it mixes with the nitrogen entering line 93 from line 91 and the resultant 10 mixed nitrogen stream consisting of a mixture of liquid and gaseous nitrogen flows into the top of the rectification column C' providing the reflux for the vapors rising through this column.

Approximately 32.5 tons per hour of nitrogen 15 is withdrawn through line 100 at a temperature of -257.5° F. and a pressure of 61 pounds and introduced into the expander 101. This corresponds to 35% of the total nitrogen introduced into the flow path 69 or 26% of the total nitrogen 20 recycled. The nitrogen leaving the expander at a temperature of -318° F. and a pressure of 3 pounds mixes with that entering line 78 from line 17 and the resultant mixed nitrogen stream enters the inlet end of flow path 66 as hereinabove 25 described.

Oxygen is withdrawn through line 103 from 30 the base of portion 74 of the column at a temperature of -294.9° F. and is introduced into the flow path 68 where it flows in indirect heat exchange 35 relation with the high pressure nitrogen. The oxygen product is withdrawn through line 104 at a temperature of 72° F. and a pressure of 2 pounds. Oxygen of 90% purity is withdrawn at a rate of 35.5 tons per hour.

35 The work required to effect compression of the nitrogen passed through the re-boilers 90 and 97 providing the necessary vapor loading of the rectification system in the above example producing oxygen of 90% purity is 8,260 horsepower. 40 For purposes of comparison it is noted that operating under substantially the same conditions but effecting vaporization of the reflux only at the base of the fractionating column, as is conventional practice, 8,710 horsepower is required. 45 Thus, this invention results in a saving of 5% of the work required to effect compression of the nitrogen in carrying out the process.

Best engineering practice dictates compressing the nitrogen in three stages to raise it to the 50 pressure of approximately 62 pounds at which it is passed through the body of liquid oxygen maintained at the base of portion 74 of the column to effect re-boiling. The amount of work required to effect such compression of the nitrogen in the 55 third stage of the present invention is 1,350 horsepower. Operating in accordance with heretofore conventional technique involving re-boiling the liquid reflux entirely at the base of the column and compressing the nitrogen in three stages 60 1,790 horsepower is required to effect the compression in the third stage. Of the work required to effect the third stage of compression, this invention, it will be noted, effects a saving of 24.5%.

65 The above saving is substantially greater when producing an oxygen product of higher purity. For example, for an oxygen of 98% purity the over-all saving in energy instead of 5% is approximately 7%, and the saving in energy required for the third stage of compression is correspondingly greater than the 24.5% value above given.

It has been found that the high pressure nitrogen stream passed through re-boiler R² or coil 70 97 effects efficient re-boiling of the reflux liquid

to provide the necessary vapor loading for section 11 and portion 74, respectively. The medium pressure nitrogen stream flowing through re-boiler R¹ or coil 99 likewise effects efficient re-boiling of the reflux liquid to provide the necessary vapor loading for section 10 and portion 73, respectively. The latter reflux liquid is at a lower temperature and hence can be re-boiled or vaporized by the nitrogen stream at a lower pressure with simultaneous condensation of this nitrogen stream. In this way a material saving in the power consumption is effected since, in accordance with the present invention, the nitrogen employed to effect re-boiling of the reflux liquid is not all compressed to the high pressure required in effecting re-boiling in re-boiler R² or coil 97 but a substantial portion, about one-fourth or even more of the nitrogen is compressed to a lower pressure and employed at this lower pressure to effect the desired re-boiling. Further by employing at least two re-boilers associated with separate zones of the rectification system, the lower zone may be made of materially smaller capacity than would otherwise be the case with consequent saving in the construction costs for the rectification equipment.

Since certain changes may be made in carrying out the above process without departing from the scope of this invention it is intended that all matter contained in the above description shall be interpreted as illustrative and not in a limiting sense. Thus, for example, while the invention has been described in connection with the production of oxygen by the liquefaction and rectification of air, it will be understood it is not limited thereto but includes the treatment of mixtures of other gases to effect their separation, for example the rectification of natural gas having an appreciable nitrogen content. While two re-boilers have been shown, it will be understood a greater number may be used spaced along the height of the fractionating column to give optimum results. When using two re-boilers in an oxygen process, the re-boiler at the intermediate level is preferably disposed at a point where the vapor in the column contains about 50% to 60% nitrogen. The other re-boiler is of course located at or near the base of the rectification column.

The term "reflux liquid" is used in the claims, to mean the liquid in the rectification column including the liquid which collects therein at the bottom of the column; thus referring, for example, to Figure 1, this term includes not only the liquid introduced through line 26 into the top of section 10 but also the liquid which collects at the base of this section.

What is claimed is:

1. A process of rectifying a gaseous mixture to recover two gaseous rectification products, each in substantial proportion, which comprises rectifying said gaseous mixture in a rectification zone through which a liquefied portion of said gaseous mixture descends from the upper end to the lower end of said zone, subjecting said liquefied portion to reboiling when passing through a region of said zone intermediate said upper and lower ends and again to reboiling when reaching said lower end, recovering a top gaseous rectification product in substantial proportion from said upper end and a bottom gaseous rectification product in substantial proportion from said lower end, compressing part of said top product, dividing the compressed part into two streams, passing one of

said streams in indirect heat exchange relation with the liquefied portion passing through the intermediate region of said zone to effect said reboiling, further compressing the other of said streams, passing the further compressed stream in indirect heat exchange relation with the liquefied portion reaching said lower end to effect again said reboiling, thereafter decompressing said two streams and discharging them into said upper end of said zone.

2. A process of rectifying air to recover gaseous oxygen and nitrogen rectification products, each in substantial proportion, which comprises rectifying air in a rectification zone through which a liquefied portion of said air descends from the upper end to the lower end of said zone, subjecting said liquefied portion to reboiling when passing through a region of said zone intermediate said upper and lower ends and again to reboiling when reaching said lower end, recovering gaseous nitrogen rectification product in substantial proportion from said upper end and gaseous oxygen rectification product in substantial proportion from said lower end, compressing part of said nitrogen product, dividing the compressed part into two streams, passing one of said streams in indirect heat exchange relation with the liquefied portion passing through the intermediate region of said zone to effect said reboiling, further compressing the other of said streams, passing the further compressed stream in indirect heat exchange relation with the liquefied portion reaching said lower end to effect again said reboiling, thereafter decompressing said two streams and discharging them into said upper end of said zone.

3. The process of claim 2 wherein the rectification zone is maintained at a gauge pressure of from 2 to 10 pounds per square inch, the compressed part of said nitrogen product is at a gauge pressure of from 35 to 55 pounds per square inch, and the further compressed stream is at a gauge pressure of from 60 to 100 pounds per square inch.

4. The process of claim 1 wherein a portion of the further compressed stream is withdrawn therefrom prior to the passage of said further compressed stream in indirect heat exchange relation with the liquefied portion, and the portion thus withdrawn is expanded with the performance of external work to produce refrigeration.

5. The process of claim 2 wherein a portion of the further compressed stream is withdrawn therefrom prior to the passage of said further compressed stream in indirect heat exchange relation with the liquefied portion, and the portion thus withdrawn is expanded with the performance of external work to produce refrigeration.
